UNITED STATES PATENT OFFICE.

WILLIAM N. OEHM AND GOMERT POWELL, OF MICHIGAN CITY, INDIANA.

NAILING MACHINE.

REISSUED

1,412,626.

Specification of Letters Patent. Patented Apr. 11, 1922.

Original application filed December 2, 1920, Serial No. 427,821. Divided and this application filed July 20, 1921. Serial No. 486,112.

To all whom it may concern:

Be it known that we, WILLIAM N. OEHM and GOMERT POWELL, citizens, respectively, of the United States and of the Kingdom 5 of Holland, and residents of Michigan City, county of Laporte, and State of Indiana, have jointly invented certain new and useful Improvements in Nailing Machines, of which the following is a specification, and 10 which are illustrated in the accompanying drawings, forming a part thereof.

The invention relates to a nailing machine including a pneumatic hammer, and adapted especially for driving the nails in floor 15 boards, particularly the flooring of cars. This application is a division of our application for Letters Patent for improvements in nailing machines filed December 2, 1920, Serial No. 427,821.

20 Among the objects of the present invention are to provide for a ready shifting of the machine and permanently positioning it for driving a nail; to provide a simple and efficient nail-feeding device, and to secure 25 rapidity of operation. Another object is to provide means for advancing the hammer to the work as the nail is being driven, this means being especially designed for use with a heavy hammer, such as must be employed 30 in driving spikes.

An embodiment of the invention is illustrated in the accompanying drawings, in which—

35 Fig. 1 is a longitudinal section of the machine, partly in elevation, on the line 1—1 of Fig. 2;

Fig. 2 is a side elevation of the machine;

Fig. 3 is a plan section on the line 3—3 of Fig. 1;

40 Fig. 4 is a sectional view on the line 4—4 of Fig. 3;

Fig. 5 is a detail section on the line 5—5 of Fig. 3; and

45 Fig. 6 is a detail section on the line 6—6 of Fig. 4.

The machine comprises a pneumatic hammer, conventionally shown at 10, and which may be of any desired construction having the usual handle 11 and controlling valve 50 12. This hammer telescopically enters a

tube 13, the lower end 14 of which is contracted to form a nipple and is provided with a sleeve having spurs 15 which will engage the board into which the nail is to be

driven and hold the machine in proper position. 55

A pedal 16, adapted to have its outer end rest loosely upon the floor, is connected by means of links 17, 18, to a pair of pull rods 19, 20, attached to the upper end of the 60 hammer casing, and a spring 21, coiled about one of the rods, as 19, and reacting between the upper end thereof and a guide bracket 22 attached to the tube 13, normally holds the hammer in elevated position. 65

A feed tube 23 enters the tube 13 laterally for delivering nails thereto, and which are fed through the feed tube from a suitable receptacle, such as a funnel 24, connected therewith by means of a tube 25. The size 70 of the tube 25 is such that the nails pass through singly, and as each nail descends it is arrested at the upper end of the tube 23 by a pivoted dog 26 projecting into its path a sufficient distance to certainly engage its head. This dog is held in nail-engaging position by means of a spring 27.

A trip arm 28 is pivoted at 29 to an arm 30 secured to the pivot of the dog 26, and projects into the path of a trip 31 carried 80 by one of the pull rods, as 20. As the hammer is moved upwardly by the action of the spring 21 the trip 31 engages below the arm 28 and turns the dog 26, releasing the nail X and permitting it to drop into the tube 85 13. As the hammer is drawn down the trip 31 passes the trip arm 28, turning it on its pivot, and this latter arm is immediately returned to its normal position by the action of a spring 32. 90

Within the lower contracted end 14 of the tube 13 there is slidably fitted a bushing 33, the bore of which is suitable to allow the passage of a nail therethrough while holding it in upright position. The downward 95 movement of the bushing 33 is limited by a screw stud 34, projecting through a longitudinal slot in the tube section 14. As the machine is positioned for the driving of a nail the bushing 33 is moved upwardly a 100 short distance by its engagement with the floor and insures the entry thereinto of the nail now within the body portion of the tube 13.

A punch or nail set 35, forming an element of the pneumatic hammer, is positioned to bear upon the nail when the latter occupies the bushing 33, and to drive it as the 105

hammer is operated. The nail set 35 has a limited longitudinal movement within the lower end of the barrel of the hammer to permit the latter to be advanced after each 5 blow is struck.

The nail feeding, positioning and driving means are not claimed in this application. In using the device the operator may keep one foot continuously on the pedal 16. After 10 driving a spike he steps forward with the foot which had rested on the floor, raises the machine by hand, and shifts it to its new position, merely relieving the pressure on the pedal to permit it to drag along the 15 floor. The form of the pedal may be varied without departing from the scope of the invention.

We claim as our invention—

1. In a nailing machine, in combination, 20 a tube provided with a nail box at its lower end, a spring-retracted pneumatic hammer reciprocable in the tube, a pedal for advancing the hammer, pivoted at one end to said hammer below the springs and having its 25 other end adapted to drag along the floor.
2. A movable nailing machine compris-

ing, in combination, a tube, a spring-retracted hammer in said tube, a handle therefor, and a pedal for advancing the hammer, pivoted thereto at one end and having its 30 other end adapted to drag along the floor.

3. A movable nailing machine comprising, in combination, a tube, a spring-retracted hammer reciprocable in the tube, and a pedal for advancing the hammer having 35 one end adapted to drag along the floor.

4. In a nailing device, in combination, a tube having a nail-positioning nipple, a spring-retracted pneumatic hammer reciprocable in the tube, a pedal for advancing 40 the hammer pivoted at one end to said hammer and having its other end adapted to drag along the floor.

5. A movable nailing machine comprising, in combination, a suitable frame, a spring- 45 retracted hammer having a handle, a pedal for advancing the hammer and having one end adapted to drag along the floor when the machine is moved forward.

WILLIAM N. OEHM.
GOMERT POWELL.
